UNITED STATES PATENT OFFICE.

JOHN THOMAS WEST, OF BOWLING GREEN, KENTUCKY.

TRACK-RAIL FASTENER FOR RAILROADS.

No. 893,962.

Specification of Letters Patent.

Patented July 21, 1908.

Application filed November 29, 1907. Serial No. 404,969.

To all whom it may concern:

Be it known that I, JOHN T. WEST, a citizen of the United States, and a resident of Bowling Green, in the county of Warren and 5 State of Kentucky, have invented a new and Improved Track-Rail Fastener for Railroads, of which the following is a full, clear, and exact description.

The purpose of this invention is to provide 10 novel, simple details of construction for a track rail fastener, that is readily applied for construction of a new railroad, or for repairing a track as may be required, the improvement being adapted for quick application, and in service is very reliable and 15 effective as a means for holding track rails secured upon cross ties of the railroad.

The invention consists in the novel construction and combination of parts, as is 20 hereinafter described and defined in the appended claims.

Reference is to be had to the accompanying drawings forming a part of this specification, in which similar characters of reference 25 indicate corresponding parts in all the views.

Figure 1 is a transverse sectional view of a track rail, a longitudinal sectional view of a cross tie in part, and a similar sectional view of the improved rail fastener, taken substantially on the line 1—1 of Fig. 3; Fig. 2 is a 30 transverse sectional view of a cross tie, a side view of a portion of a track rail, the section being indicated by the line 2—2 of Fig. 3, and a side view of the improvement applied for securing the track rail in place on the cross tie; Fig. 3 is a plan view of the details shown in Figs. 1 and 2; Fig. 4 is a 35 detached perspective view reduced in size, of a track rail chair that is a detail of the invention; and Fig. 5 is a detached perspective view of a novel clamp employed for holding a track rail secured on the chair.

In the drawings which illustrate the construction and application of the invention, 40 A indicates a track rail of the usual construction having a ball or head a, web b, and foot flanges d, d' that project oppositely from the lower termination of the web.

B represents one of an indefinite number 45 of cross ties, preferably formed rectangular in cross section, of wood or other available material.

The chair that is an essential detail of the improvement, is formed of metal either 50 wrought or cast into form, and comprises a flat seat plate e, that is of a suitable length,

and a width equal to that of a cross tie it is to be mounted upon, and on the seat plate two side flanges e', e'', are formed, that are of equal width, and equal in length that of 55 the seat plate, said flanges being spaced apart in parallel planes, whereby they are adapted for closely embracing the tie B as represented in Fig. 2.

There are two integral hook-like flanges g, 60 g' on the seat plate, that may be formed of material thereof cut loose therefrom at their side edges, and bent toward each other over and spaced from the intermediate portion of the seat plate, as is clearly shown in Fig. 4. 70 In applying the device for the reception of a track rail such as A, the chair e is mounted at a proper point on a cross tie B, and is secured thereon by a bolt h that passes through the flanges e' and the tie B, which arrangement 75 of parts disposes the return bent flanges g, g' transversely above the seat plate of the chair. The track rail A is now seated upon the chair and slid into position between the flanges g, g', and one of said flanges g, receives 80 the free side edge of a corresponding foot flange d of the track rail, and laps thereover as shown in Fig. 1.

A completing detail of the rail fastener consists of a rail clamp for engaging the remaining hook flange g', and the adjacent foot flange d' as clearly shown in Fig. 5, embodying a clamping flange i, integrally formed on one side edge of a wedge-like key-plate i', that at one end is provided with an upwardly-turned offset-head ii, and at the opposite end that is thinnest, is vertically perforated for the reception of a split key i'.

It will be noticed that if the track-rail is in 85 position on the seat-plate as before explained, a sufficient space will be afforded between the side edge of the foot-flange d' and the return-bent flange g', to permit of the key plate i' being driven therebetween, thus binding the clamping flange i against and upon the 100 foot-flange d', which also serves to press the rail laterally, so as to clamp the flange g upon the foot-flange d, and thus secure the track-rail A in position on the chair, and by an insertion of the split key i' the key-plate is prevented from complete retraction.

Having thus described my invention, I claim as new and desire to secure by Letters Patent:—

1. A railroad track rail fastener, comprising 110 a chair adapted to seat transversely of the tie, and having spaced depending flanges for en-

gaging the sides of the tie, and upwardly and inwardly projecting flanges for receiving the base of the rail therebetween, a key plate having a clamping flange projecting therefrom at one side edge thereof, said key being adapted to be received beneath one of the last named flanges with the clamping flange seating on one side of the rail base, the other side of said rail base being seated beneath 10 the opposite flange, a pin traversing the key and the chair, said key having a flange at the end thereof, to limit its inward movement.

2. A railroad track rail fastener, embodying a chair having two spaced parallel pending flanges thereon, two return bent flanges at the ends of the chair, receiving a track rail between them, one flange bearing upon a respective flange on the track rail and the other return bent flange

spaced from the opposite foot flange on the 25 track rail, a key plate in wedge form, having an offset head on one end thereof, and a perforation in the opposite end, an integral clamping flange on one side edge of the key plate which bears upon the opposite foot 30 flange of the track rail when the key plate is driven into place, a split key engaging the perforation in the key plate, and a bolt adapted for securing the lateral flanges on the chair, clamped upon a railroad cross tie. 35

In testimony whereof I have signed my name to this specification in the presence of two subscribing witnesses.

JOHN THOMAS WEST.
